UNITED STATES PATENT OFFICE.

ALBERT H. MARANDA, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

MACHINE FOR CONTROLLING RAILWAY-TRAFFIC-GOVERNING APPARATUS.

Application filed July 29, 1926. Serial No. 125,700.

My invention relates to machines for controlling railway traffic governing apparatus, and particularly to machines of the type comprising levers for the mechanical operation of traffic governing devices and other levers for the electrical control of traffic governing devices.

I will describe one form of machine embodying my invention, and will then point out the novel features thereof in claims.

In the accompanying drawings, Fig. 1 is a view showing in front elevation one form of machine embodying my invention, with a portion of the machine broken away to better illustrate the construction. Fig. 2 is an end view partially sectioned showing the machine illustrated in Fig. 1.

Similar reference characters refer to similar parts in both views.

Referring to the drawings, the reference character A designates a suitable framework in which are supported a plurality of mechanical levers B. Each of these levers is pivoted near its lower end at 1 and is adapted for the mechanical operation of a railway traffic governing device, such as a railway switch. An interlocking bed C is also supported by the framework A and comprises a plurality of locking bars 2. Each lever B is provided with a latch 3 for co-operating with a latch plate 4 to retain the lever B in the extreme positions of its stroke, and this latch operates a locking link 5, one end of which is operatively connected with a crank 6. This crank is fastened to a rotating shaft 7 which is arranged to operate one or more of the locking bars 2 by suitable means such as a jaw 8 to shaft 7 and engaging a driving lug attached to the locking bar. The movements of each latch 3 are thus utilized to impart longitudinal motion of one or more of the locking bars 2. Mounted also on the framework A are one or more electrical control mechanisms each comprising an electric lever 9. The machine may be provided with as many of these electric levers as are required for the operation of traffic governing devices and as shown in the drawing the machine comprises two electric levers.

Each lever 9 operates a shaft 10 through the medium of bevel gears 11. A crank 12 is rigidly attached to each shaft 10 and op-

erates a rod 13 by means of which the shaft 10 may be connected with any selected one or ones of the locking bars 2.

Two of the shafts 7 are provided with bushings 16 which are journaled in bearings 15 in a hanger 14. Supported upon the same two shafts in similar manner is a second hanger 14^a located in spaced relation with, and parallel to hanger 14. A plurality of counter-shafts 17 provided with bushings 18 are journaled in the hangers 14 and 14^a to permit free rotation of the counter shafts. It will be seen that each of the hangers 14, 14^a is supported solely by the shafts 7 so that the hanger is held rigidly in position but permits free rotation of the shafts 7. The rod 13 operated by the electric lever 9 is connected with one of the counter-shafts 17 by means of a crank 19. A second crank 19^a also attached to the same counter-shaft operates a driver 21 mounted to rotate freely on an adjacent shaft 7. The driver 21 is connected with the crank 19^a by means of a link 20, and is provided with a segment gear 23 which meshes with teeth cut in one of the locking bars 2. It will be seen that the counter-shaft 17 may be provided with any reasonable number of cranks 19^a for operating a similar number of drivers 21 so that a single electric lever 9 may operate any number of locking bars 2 without interfering with the usual operation of the locking bed by the mechanical lever shafts 7. Other levers 9 may be connected with the remaining counter-shafts 17 as will be clear from the foregoing explanation.

It should also be pointed out that while I have shown the hangers 14 and 14^a of such size as to carry four counter-shafts 17, this particular arrangement is not essential but the hangers may be of any suitable size. Furthermore, they may be supported by any selected ones of the shaft 7 and may be moved to any part of the machine where it is desirable to operate a locking bar by an electric lever. Similarly, the length of the counter-shafts 17 depends entirely upon the bar or number of bars to be operated thereby and upon the spaces available for supporting the bushings 16, so that the counter-shafts 17 may be long or short depending upon the particular installation.

Although I have herein shown and de-

scribed only one form of machine embodying my invention, it is understood that various changes and modifications may be made therein within the scope of the appended claims without departing from the spirit and scope of my invention.

Having thus described my invention what I claim is:

1. In an interlocking machine comprising 10 mechanical levers, a latch for each lever, a plurality of rotatable shafts one operatively connected with each latch, a mechanical interlocking bed comprising a plurality of locking bars one of which is operatively connected with each said shaft, and an electric lever; the combination with the above-mentioned instrumentalities of a counter-shaft 15 operated by said electric lever, and a driving crank attached to said counter-shaft for operating one of said locking bars.

2. The combination, in an interlocking machine, of a mechanical lever provided with a latch, a mechanical locking bed comprising a plurality of locking bars, one of which is operatively connected with said latch, an electric lever, a rotatable counter-shaft operated solely by said electric lever, and mechanism for operatively connecting said counter-shaft with another of said locking 25 bars.

3. In an interlocking machine comprising 30 mechanical levers, a latch for each said lever, a plurality of rotatable shafts one operatively connected with each latch, a mechanical interlocking bed comprising a plurality of locking bars one of which is operatively connected with each said shaft, and an electric lever; the combination with the above-mentioned instrumentalities of a hanger supported by two shafts but permitting free ro- 35

45 tation of the shafts, a counter-shaft journaled in said hanger and connected with said electric lever, and means for operatively connecting said counter-shaft with one of said locking bars.

4. In an interlocking machine comprising 50 mechanical levers, a latch for each said lever, a plurality of rotatable shafts one operatively connected with each latch, a mechanical interlocking bed comprising a plurality of locking bars one of which is operatively connected with each said shaft, and an electric lever; the combination with the above-mentioned instrumentalities of a counter-shaft operated by said electric lever, a driver 55 mounted to rotate freely on one of said shafts but operatively connected with a locking bar, and mechanism interposed between said driver and the counter-shaft.

5. In an interlocking machine comprising 60 mechanical levers, a latch for each said lever, a plurality of rotatable shafts one operatively connected with each latch, a mechanical interlocking bed comprising a plurality of locking bars one of which is operatively 65 connected with each said shaft, and an electric lever; the combination with the above-mentioned instrumentalities of a pair of hangers supported solely by two of said shafts but permitting free rotation of such 70 shafts, a counter-shaft freely rotatable in said hangers and operatively connected with said electric lever, a driver mounted to rotate freely on one of said shafts but operatively connected with a locking bar, a crank, 75 rigidly fastened to the counter-shaft, and a link for connecting said driver and said crank.

In testimony whereof I affix my signature.

ALBERT H. MARANDA.
